UNITED STATES PATENT OFFICE

162,769

COMBINATION TABLE AND CABINET

Eric G. Arnell, Oakland, Calif.

Application January 3, 1950, Serial No. 6,977

Term of patent 7 years

(Cl. D33—19)

To all whom it may concern:

Be it known that I, Eric G. Arnell, a subject of the King of Sweden, and a resident of Oakland, Alameda County, California, have invented a new, original, and ornamental Design for a Combination Table and Cabinet, of which the following is a specification, reference being had to the accompanying drawing, forming part thereof.

Figures 1 and 2 are perspective views of reverse sides of the combination table and cabinet, showing my new design, the doors of the cabinet being respectively shown closed and open in the different views.

I claim:

The ornamental design for a combination table and cabinet, substantially as shown.

ERIC G. ARNELL.
